L.B. Wakeman.

Sails & Rigging

N° 22,683.

Patented Jan 18, 1854

UNITED STATES PATENT OFFICE.

L. B. WAKEMAN, OF BALTIMORE, MARYLAND.

DEVICE FOR REEFING SAILS.

Specification of Letters Patent No. 22,683, dated January 18, 1859.

To all whom it may concern:

Be it known that L. LOUIS B. WAKEMAN, of the city of Baltimore and State of Maryland, have invented certain new and useful Improvements in Reefing or Furling Sails from the Decks of Vessels; and I do hereby declare that the following is a full, clear, and exact description of the same, reference being had to the accompanying drawings, making a part of this specification.

In my method of reefing and furling no extra weight or additional spar is requisite, as the sail or sheet is rolled around the usual spar employed (in the common rig,) in a simple and effective manner: while the studding sail booms are made to subserve the additional purpose of a chafing bar in protecting the reefed said from chafe on the shrouds.

The following description will enable others skilled in the art of marine to understand and use my improvements.

A represents the mast of a vessel; B, the lower yard, which is slung in the usual manner.

C is the top sail yard, formed with the ordinary taper, but provided at its ends with swiveling bands *a a* each band provided with projecting arms (*b*) for carrying small blocks fitted thereon, so as to admit of every change in position requisite to insure the proper leading of the windlass ropes *d d* passing to the mast and thence to the deck and windlass. This swivel band (as the description of one will suffice) is further provided with an arm *c*, at right angles to *b*, forming a boom iron or this iron may be forked and carry two rings through which the boom D passes that carries the studding sails; said booms are furnished on their inner ends with drop hooks for entering eyes made in the truss bands when the booms are slid in and then the two booms serve the purpose and form a chafing bar.

The yard C, is supported by a smooth faced clamp, which also forms the truss band surrounding the mast. It is so formed that the lower part E' of the clamp forms one-half of said truss band, while the projecting portion thereof passes upward and forms a socket in which the yard may lie. The upper portion E of the clamp nearly completes the encircling of the yard and it is attached to the lower jaw of the clamp by a screw bolt and nut. The after part (L) of the truss band is bolted to the above described portion E', thus forming a truss

embracing the mast and also a clamp encircling the yard.

The screw bolt (5) extends above the clamp and being forked carries the two blocks, through which the rolling halyards (*d'*) pass, as they are wound or unwound upon the yard in furling or unfurling the sail. By removing this screw bolt the upper part of the clamp may be detached and allow of the lifting out of the yard.

The manner of working my improvement is as follows: To take the sail in let go the standing rolling halyards *d'' d''* keeping taut the windlass ropes *d, d* when the yard will descend by its own weight, winding the rolling halyards *d'* with the sail on the yard, each roll of the sail taking with it a turn of the halyards. The yard having descended to the crosstrees if any slack sail is below, then haul taut the windlass ropes *d, d* and ease off the sheets 4, 4, when the yard will revolve and complete the furl. To raise the sail, haul upon the rolling halyards and upon the sheets 4, until the lower part of the sail is spread, fasten the sheets and continue the haul on the halyards which will cause the ascent of the yard and unrolling of the sail, at the same time winding the windlass ropes around the ends of the yard.

In bending or unbending a sail the rolling halyards may be used to advantage when the yard is down at the cross trees. Thus in unfurling the sail ease off the windlass ropes and haul on the rolling halyards, or vice versa, in furling. The advantage gained is that of easing the strain on the clamp and dispenses with the raising of the yard from the cross trees.

What I claim as my invention and desire to secure by Letters Patent is—

1. The employment of the smooth surfaced clamp E E' as described when in combination with the forked screw bolt 5 or its equivalent carrying the blocks through which the rolling halyards *d' d'* pass, for the purposes set forth.

2. I also claim giving direction to windlass ropes *d d* by the bent arm *b* when in combination with the clamps E E', and forked screw bolt 5 fitted with an ordinary block operating in the manner and for the purposes set forth.

In testimony whereof I have signed my name before two subscribing witnesses.

L. B. WAKEMAN.
